(57) **CLAIM**

The ornamental design for a woman's undergarment, as shown and described.

DESCRIPTION

FIG. 1 is a front perspective view of an woman's undergarment showing my new design;

FIG. 2 is a front elevational view thereof;

FIG. 3 is a rear elevational view thereof;

FIG. 4 is a right side elevational view thereof, the left side being a mirror image thereof;

FIG. 5 is a top plan view thereof, shown as it would look when worn by a wearer (not shown);

FIG. 6 is a bottom plan view thereof, shown as it would look when worn by a wearer (not shown);

FIG. 7 is a front elevation view, shown as it would look when worn by a wearer (not shown); and,

FIG. 8 is a rear elevation view thereof, shown as it would look when worn by a wearer (not shown).

The broken line showing of the human figure in FIGS. 1 and 4 illustrates the environment in which the design is used, assists in showing how the claimed design appears when worn, and forms no part of the claim.

The tight broken line showing on the woman's undergarment in FIGS. 1-8 represents stitching.

The fragmentary cris-cross pattern shown in FIGS. 1-8 represents fabric and is repeated uniformly throughout the areas shown.

The fragmentary stippled pattern shown in FIGS. 1-8 represents mesh fabric and is repeated uniformly throughout the areas shown.
